FLOOR POLISHING ATTACHMENT FOR
SUCTION CLEANERSNelson W. La Briere, Canton, Ohio, assignor to
The Hoover Company, North Canton, Ohio, a
corporation of Ohio

Application June 3, 1949, Serial No. 96,894

3 Claims. (Cl. 15—328)

1

This invention relates to a floor polishing attachment for suction cleaners and more particularly to means for preventing the usual rear wheels of the suction cleaner from marking or marring the polished surface of the floor.

Polishing attachments for suction cleaners are well known in the art. The usual agitator or brush is removed from the suction nozzle and an attachment applied thereto in the form of a large polishing brush which raises the front wheels of the cleaner free of the floor.

However, prior polishing attachments for suction cleaners made no provision for preventing the rear wheels of the cleaner from marking or marring the polished surface produced by the attachment. As a result such polishing attachments have not been satisfactory and have not been generally accepted.

When a polishing attachment is applied to a suction cleaner no suction is necessary. As a result it has been proposed to block off the exhaust nozzle of the cleaner to reduce the load on the motor. However, it is necessary that some air be circulated through the cleaner to prevent the usual rubber agitator driving belt from becoming hot and deteriorating.

According to the present invention a cover plate is provided for the exhaust outlet to block off the major portion of the air being handled by the fan but having louvers permitting a limited circulation of air and a polishing or non-marking support is attached to the cover plate for raising the rear wheels from the floor to prevent them from marking or marring the polished surface.

Other objects and advantages of this invention will become apparent as the description proceeds when taken in connection with the accompanying drawings in which:

Figure 1 is a perspective view of a suction cleaner with the polishing attachment of this invention applied thereto; and

Figure 2 is a plan view of one form of the non-marking support for raising the rear wheels from the surface being polished.

Referring to Fig. 1, the suction cleaner to which this invention is applied comprises a main frame 10 including a suction nozzle 11 at its forward end and a propelling handle 12 pivotally attached to its rear end. The main frame houses the usual suction fan driven by a motor housed within the hood 13 with a handle control release pedal 14 extending through one side thereof.

A rotary agitator (not shown) is usually posi-

tioned in the nozzle 11 and is normally driven by a belt from the pulley 15 carried by the fan shaft. The suction passageway in which the belt and pulley is normally placed is closed by a removable cover plate (not shown) since it has been removed for the application of a polisher attachment of this invention. Normally, the fan produces a suction at the nozzle 11 and discharges through an exhaust outlet 16.

10 The cleaner is normally mounted for ambulatory movement on front wheels 17 and rear wheels 18 movably mounted relative to the main frame for adjusting the position of the nozzle relative to the surface upon which the cleaner rests in a manner known to the art.

In converting the suction cleaner above described to a floor polisher the suction passageway cover plate and the usual agitator are removed. A polishing attachment in the form of an attachment 20 is detachably secured to the nozzle 11 and rotatably carries a large polishing brush 19 driven by a belt 21 extending over the pulley 15. The polishing brush 19 is of sufficiently large diameter and of sufficient stiffness to raise the front wheels 17 from the floor being polished.

15 In order to reduce the load on the fan the exhaust opening 16 is closed by a plate 22 having a louver 23 to provide for limited circulation of air to prevent the cleaner from overheating. The closure plate 22 is attached to the exhaust opening 16 by the bolts usually used in attaching a filter bag to the cleaner.

20 The plate 22 is extended downwardly at 24 and is provided with a non-marking, non-marring support in the form of a roller 25 to raise the rear wheels from the surface being polished.

While the roller 25 has been shown in the drawings it is merely an example of the broader aspects of this invention. Any polishing or non-marking support may be utilized.

25 In the arrangement shown the roller 25 may be of wood or other material having a non-marking or polishing covering applied.

30 Preferably, however, the roller 25 is made of solid rubber 30 as shown in Fig. 2. A cadmium plated pin 31 is forced axially through the center of the solid rubber roller 30 and has pintles 32 supported in ears 33 extending rearwardly from the extension 24. Spacing washers 34 are provided for spacing the ends of the rubber roller 30 from the ears 33 to provide a good thrust bearing surface.

35 By a non-marking or a non-marring support,

as used herein, is meant any support with a soft floor engaging surface, rotary or otherwise, or a rigid support with a smooth floor contacting portion of sufficient extent that the weight of the cleaner may be supported on a waxed and polished surface without making marks thereon.

From the foregoing it can be seen that this invention provides a polishing attachment for a suction cleaner in which both the front and rear wheels which usually support the cleaner for ambulatory movement is raised upwardly from the surface being polished by the polishing brush and by a non-marring support secured to the cover plate for the exhaust nozzle.

While I have shown and described but a single embodiment of my invention it is to be understood that this embodiment is to be taken as illustrative only and not in a limiting sense. I do not wish to be limited to the particular structure shown and described but to include all equivalent variations thereof except as limited by the scope of the claims.

I claim:

1. In a suction cleaner having front and rear wheels for supporting it for ambulatory movement, a downwardly facing suction nozzle, a power transmitting belt extending into said nozzle, an exhaust port at the rear thereof, and a rotary agitator normally supported in said nozzle, that improvement which comprises, a large diameter polishing brush rotatably sup-

ported in said nozzle in place of said agitator, said brush being formed to be driven by said power transmitting belt, and being of sufficient diameter and of sufficient stiffness to support said front wheels above the surface to be polished, a louvered closure plate for said exhaust port, said closure plate having a portion extending downwardly below said exhaust port towards said rear supporting wheels and an auxiliary non-marring support attached to said downward extending portion for supporting said rear wheels out of contact with the surface being polished.

2. The combination of claim 1 in which said auxiliary support is in the form of a non-marring roller journaled to said closure plate.

3. The combination of claim 2 in which said roller is made of solid rubber with its shaft forced axially through its axial center.

NELSON W. LA BRIERE.
